FASTENING-INSERTING MACHINE

Fred N. La Chapelle, Beverly, Mass., assignor to
United Shoe Machinery Corporation, Paterson,
N. J., a corporation of New Jersey

Application January 13, 1932, Serial No. 586,390

24 Claims. (Cl. 1—30)

This invention relates to fastening inserting machines and is illustrated herein as embodied in a fibre peg inserting machine adapted for use in attaching soles to shoe bottoms.

It is present day practice to attach leather outsoles to shoe bottoms, for example, at their heel seat portions, by fibre pegs of the character disclosed in Letters Patent of the United States No. 1,729,169, granted Sept. 24, 1929, on an application filed in my name. Such pegs are driven without difficulty into leather soles by a machine provided with work penetrating awls. The pegging of rubber soles is not, however, accomplished so readily since the awl holes close up when the awl is withdrawn and there is danger of crippling the peg, particularly if it is presented even very slightly out of line with the hole.

It is accordingly an object of the present invention to provide an improved fastening inserting machine well adapted for use in attaching rubber soles to shoes. I have found that the crippling of the pegs can be prevented in rubber sole work if the pegs are supported during the inserting operation at the point of peg insertion by means which is arranged also to apply a compressing force to the rubber of the sole in the direction of fastening insertion. By thus supporting the peg the entering end of the peg, while permitted to find the hole in the sole made by the awl, is supported against deflection even though there be some displacement of the rubber of the sole because of a misalignment of the peg and the hole. By placing the rubber under compression I reduce the thickness of the sole at the place where a fastening is to be inserted, so that not only is spreading or bending of the upper end of the peg prevented by the support which is held firmly in engagement with the compressed portion of the sole but, when the pressure is released the rubber closes about the upper end of the peg which, by reason of the manner in which the peg has been controlled and supported, has maintained substantially its original form.

The machine herein shown includes in its organization a nozzle or throat member arranged to sever fiber fastenings from a strip of fiber fastening material and to present the fastenings to the operation of a driver for insertion into holes formed in the work by an awl. In a machine of this character it is convenient to utilize the nozzle or throat member of the machine to support the pegs at the point of peg insertion and also to apply a compressing force to the

rubber of the sole in the direction of the length of the fastening receiving hole formed therein by the awl. Thus during the inserting operation a continuous support for the fastenings is provided between the driver of the machine and the surface of the work. Such an organization comprises a feature of my invention. In the construction shown, means is accordingly provided, operative after the throat member has completed its movement toward the driver, to press the throat member downwardly into forceful engagement with the work preparatory to and during the fastening inserting operation and then to return the throat member to its uppermost position. As illustrated, this means is yieldingly and adjustably connected to the throat member and includes a spring the initial tension of which may be regulated and through which force is transmitted to thrust the throat member downwardly into engagement with the work to compress the rubber of the sole until a resistance is encountered which causes the spring to yield and to permit the throat member to come to rest.

Although the illustrated machine will be hereinafter described with special reference to its use for attaching rubber soles to shoes, it will be readily seen that the invention is not restricted in its application to such use but is capable of being usefully employed for other purposes including the attachment, for example, of leather soles to shoes in which case the throat member may be moved into engagement with the work to form a continuous passage for the peg, the means for forcibly thrusting the throat member toward the work being arranged to yield when the throat member contacts with the surface of the leather sole.

With the above and other objects and features in view, the invention will now be described with reference to the accompanying drawings and will be pointed out in the claims.

In the drawings,

Fig. 1 is a side elevation of the head of a fastening inserting machine embodying the present invention;

Fig. 2 is a front elevation of the head of the machine of Fig. 1;

Fig. 3 is a plan view on an enlarged scale of the throat operating slide; and

Fig. 4 is a side elevation on an enlarged scale of the throat member and showing a cross section of a shoe mounted upon a last and presented to the machine as for the performance of the heel-seat nailing or pegging operation.

The illustrated machine is of the general type disclosed in Letters Patent of the United States No. 1,030,775, granted June 25, 1912 upon an application filed in the name of George Goddu, 5 though organized to insert fibre pegs severed from a strip of fastening material such as paper twine instead of loose nails in the same manner as in the machine disclosed in United States Letters Patent No. 1,849,253, granted March 15, 10 1932, on an application filed in my name. The machine may be advantageously equipped with a work support and controlling mechanism therefor of the character disclosed in an application for Letters Patent of the United States, 15 Ser. No. 515,047 filed February 11, 1931 in my name to which reference may be had for a full disclosure of such parts of the machine as it is unnecessary to illustrate herein.

The illustrated machine is provided with a 20 column 10 carrying a head 12 on which are mounted the fastening inserting instrumentalities of the machine. The column 10 also carries a work support terminating in a last pin 14 (Fig. 1) arranged to support a work piece such 25 as a shoe 16 mounted upon a last 18 with its sole 20 in engagement with a presser plate or abutment 22 carried by the head 12 of the machine. The shoe may be positioned relatively to the fastening inserting instrumentalities of 30 the machine by a gage 24 which can take any suitable form also carried by the head 12 of the machine.

Mounted in suitable bearings carried by the 35 head 12, of the machine is a cam shaft 30 (Fig. 2) carrying a cam member 32 provided with a series of cam grooves and surfaces arranged to operate the moving parts of the machine. The cam shaft 30 is connected to a pulley 34, driven from any suitable source of power by 40 a belt 36, by means of a clutch (not shown) having a driving surface and a breaking surface and operating substantially as disclosed in said Letters Patent of the United States No. 1,030,775 referred to above. The machine is provided with 45 a driver bar 40 mounted for reciprocating movement in vertical ways carried by the head 12 of the machine adjacent to the forward end of the shaft 30. Clamped to the lower end of the driver bar 40 is a driver 42. The driver bar 40 is provided with a rack 44 meshing with a gear segment 46 formed upon the end of the forwardly extending arm of a bell crank lever 48 fulcrumed at 50 to the head 12 of the machine and having a depending arm carrying at its lower end a roll positioned in a cam track 52 formed in the cam member 32.

The illustrated machine is provided with an awl 60 which serves to form fastening receiving holes in the work piece presented thereto and to 60 feed the work piece toward and past the driver 42. The awl 60 is secured to the lower end of an awl bar 62 mounted for vertical sliding movement in ways formed in an awl bar carrier 64. The awl bar carrier 64 is reciprocated 65 transversely of the machine by a lever 66 fulcrumed to the head 12 of the machine and carrying a roll positioned in a cam groove formed in the rear portion of a cam disk 68 secured to the forward end of the shaft 30. The awl 70 60 is moved downwardly to form fastening receiving holes in the work by mechanism (not shown) which may be and preferably is of the type disclosed in Letters Patent No. 1,849,253 hereinbefore referred to, which mechanism includes means arranged to permit the awl to come

to rest when it encounters an excessive resistance in its work penetrating movement as when the awl strikes the metal bottom plate 19 of the last 18.

The machine is provided with a throat member 70 carried by the forward end of a lever 72 fulcrumed at 74 to a bar 76 and mounted for forward and rearward movement with the bar 76 in ways carried by the head 12 of the machine. The bar 76 is provided near its rear end with a rack 78 meshing with a gear segment 80 formed at the lower end of a lever 82 fulcrumed at 84 to the head 12 of the machine and carrying a cam roll 86 positioned in a cam groove 88 formed in the cam member 32. 80 85 90

The fibre fastening material 90, from which the pegs inserted by the machine are severed, is carried by a reel 92 mounted upon a bracket 94 secured to the head 12 of the machine (Fig. 1). In the illustrated machine the fibre fastening material 90 is fed through a passage-way 91 (Fig. 4) the lower end of which is in alignment with the driver passage of the throat member 70 when the latter is in its rearmost position by feeding mechanism preferably, though not necessarily, of the type disclosed in Letters Patent No. 1,849,253 referred to above and the length of each feeding movement of the feeding mechanism is controlled by mechanism of substantially the same construction as that shown in said Letters Patent so that fibre pegs will be severed from the fastening material 90 as the throat member 70 moves forwardly each of a length determined by the thickness of the work piece at the point where it is to be inserted. The feeding mechanism includes a feed dog 100 (Fig. 2) pivoted to a block 102 formed at the end of a tubular member 104 which forms a guide for the fastening material 90 and is mounted for reciprocating movement lengthwise 105 of the strip of fastening material 90 in a slide-way formed in a bracket 106 secured to the head 12 of the machine. The extent of the reciprocation of the block 102 will determine the length of fastening material fed. Accordingly, 110 the machine is so organized that the reciprocation of the block 102 is controlled by the awl bar 62 and bears a definite relation to the distance which the awl is projected below the presser plate 22 of the machine in each cycle 115 of operation. Accordingly, the block 102 is pivoted to a block 103 mounted in slidways formed at the forward end of a lever 110 fulcrumed at 120 to the head 12 of the machine and having a rearwardly and forwardly extending arm 125 pivoted at 114 to the forward end of the link 116. The link 116 is pivoted intermediate between its ends to the forward end of another link 118 the rear end of which is adjustably pivoted by a bolt and slot connection 120 to 130 a lever 122 fulcrumed at 124 to the head 12 of the machine and provided with a rearwardly extending arm carrying a roll positioned in a cam track 126 formed in the cam member 32. As illustrated the lever 122 is effective also to 135 transmit the pressure relieving movement to the work support 14 which facilitates the feeding of the work, that movement being transmitted through a rod 128 to mechanism of the character fully shown and described in application Serial No. 515,047 hereinbefore mentioned. The rear end of the link 116 is provided with a slide member positioned in an arcuate slot 130 formed in the upwardly and rearwardly extending arm of a lever 132 fulcrumed at 134 140

145 150

to the head 12 of the machine and having a forwardly extending arm provided with a gear segment 136 meshing with a gear segment 138 formed upon the rearwardly extending arm of a lever 140 fulcrumed at 142 to the head 12 of the machine and having a forwardly extending arm 144 provided with a gear segment (not shown) meshing with a rack formed upon the rear surface of the awl bar 62. Thus it will be seen that the lever 132 will be rocked through an angle which is determined by the extent of the reciprocation of the awl bar 62. The slot 130 has a radius of curvature equal to the effective length of the link 116 and the lever 132 is so positioned that the slot 130 is concentric with the pivot 114 between the lever 110 and the lever 116 when the parts are in the position which they occupy when the entering end of the awl 60 is flush with the lower surface of the presser plate 22. As the awl 60 descends below this position the lever 132 is rocked in a counter-clockwise direction, as viewed in Fig. 1, the extent of this rocking movement depending upon the distance which the awl moves before it is stopped by impact with the metal bottom plate 19 of the last 18. Thus the rocking movement of the lever 122, which is uniform in each cycle of operation of the machine, is varied as it is transmitted to the lever 110, the extent of the rocking movement of the lever 110 increasing with the increased eccentricity of the slot 130 relatively to the pivot 114 caused by an increased work penetrating movement of the awl 60. The bolt and slot adjustment 120 between the lever 122 and the link 118 permits the length of the fastening material fed to be increased a greater or less amount over the thickness of the work piece penetrated by the awl 60.

The lever 72 is yieldingly and adjustably connected at its forward end to a lever 150 pivoted at 152 to the head 12 of the machine and having a laterally extending arm carrying a roll 154 positioned in a cam groove 156 formed in the front portion of the cam plate 68. Connected to the forward end of the lever 72 by a ball and socket joint is an upwardly extending threaded rod 158 surrounded by a compression spring 160 bearing at its lower end against one of a pair of adjusting nuts 162 mounted on the rod 158 and at its upper end against a shoulder formed on a nipple 164. The nipple 164 is provided with a globular end retained in a hollow seat formed in the forward end of an arm 166 of the lever 150 and has a central aperture through which passes the reduced end portion of the rod 158 on the upper end of which is mounted a washer 170 and a pair of adjusting nuts 172.

In the operation of the machine a last 18 upon which the shoe 16 is mounted is placed on the last pin 14 of the work support. The work support is then moved upwardly to clamp the shoe 16 yieldingly against the presser plate 22, the shoe being positioned by the gage 24 in the manner usual for performing the heel seat nailing operation after which the work support is locked in said position against downward movement during operation of the fastening inserting instrumentalities by mechanism of the type disclosed in application Serial No. 515,047 hereinbefore referred to. When the machine is started the awl 60 is thrust downwardly into the sole until its lower end comes substantially into contact with the metal bottom plate 19 of the last 18 (Fig. 1). The awl is then moved transversely to the left (as viewed in Fig. 2) feeding the work piece and bringing the awl into the line of drive. The awl is then withdrawn and returned to the position which it occupied at the beginning of the cycle of operation. The work penetrating movement of the awl which has just been described is effective through the connection between the awl bar 62 and the lever 132 to rock the lever 132 in a counter-clockwise direction, as viewed in Fig. 1, to a position which is determined by the thickness of the shoe bottom, as measured by the movement of the awl, thus controlling the angular relation between the link 116 on the one hand and the lever 132 and the link 118 on the other so that the rocking movement of the lever 140 rocks the lever 110 to an extent sufficient to cause the latter to move the block 102 through a path which causes the feed dog 100 and a surface formed on the block 102 with which the dog 100 cooperates to move through a path sufficient to feed the fastening material a distance equal to or if desired slightly more than the thickness of the shoe bottom parts which the awl 60 penetrates.

The fibre fastening material 90 is then severed by the forward movement of the throat member 70 and is brought forward into line with the driver 42 after which the cam 156 rocks the lever 150 in a counter-clockwise direction as viewed in Fig. 2 compressing the spring 160 and forcibly thrusting the throat member 70 downwardly into engagement with the sole to compress the rubber of the sole in the direction of the fastening receiving hole formed therein by the awl 60 (Fig. 1). At this time a dwell is preferably provided in the movement of the lever 150 while the driver 42 descends to drive the fastening into the hole formed in the work after which the cam 156 rocks the lever 150 in a clockwise direction to return the throat member 70 positively to its uppermost position.

Since the initial tension of the spring 160 may be adjusted by movement of the nuts 162 it will be readily seen that the force transmitted to the throat member 70 through the spring 160 may be varied so that the throat member 70 will be pressed with more or less force against the surface of the sole. I have found in operating upon rubber soles that by increasing the tension of the spring 160 sufficiently to cause a substantial compressing force to be applied to the sole not only is the entering end of the peg more firmly supported against crippling but since the thickness of the compressed portion of the sole is less than the length of the fibre peg, as measured by the work penetrating movement of the awl, the upper end of the peg is supported against spreading at the end of the fastening inserting stroke of the driver by the walls of the driver passage in the throat member. Thus when the pressure on the sole is released by the return of the throat member 70 to its uppermost position the rubber of the sole closes about the upper end of the peg which has retained its original form.

Having thus described my invention, what I claim as new and desire to secure by Letters Patent of the United States is:

1. In a fastening inserting machine, the combination with a driver and an awl arranged to form fastening receiving holes in a work piece presented thereto, of means movable relatively to said awl for transferring fastenings into the path of movement of the driver and for support-

- ing the fastenings at the point of fastening insertion, said means being arranged for movement toward the work to compress the work at the point of fastening insertion. 80
5. 2. In a fastening inserting machine, the combination with a driver and an awl arranged to form fastening receiving holes in a work piece presented thereto and to feed the work piece to bring the fastening receiving hole into alignment with the driver, of means movable relatively to said awl toward the driver to present fastenings for insertion into the work and thereafter movable toward the work to support the fastenings as they are inserted into the work. 85
10. 3. A fastening inserting machine having, in combination, a driver, an awl arranged to form fastening receiving holes in the work and to feed the work to bring the fastening receiving hole formed therein into alignment with the driver, and means movable in a path transverse to the path of feed of the work and toward the driver to present fastenings for insertion into the work and thereafter movable toward the work to provide a continuous passage for the fastenings between the driver and the surface of the work. 90
15. 4. A fastening inserting machine having, in combination, a driver, an awl for forming fastening receiving holes in a work piece presented thereto and for feeding the work piece to bring the fastening receiving hole into alignment with the driver, and means arranged to sever fastenings from a strip of fastening material and to move the fastenings into line with the driver, said means being movable also in the line of fastening insertion into engagement with the work to prevent crippling of the fastenings. 95
20. 5. A fastening inserting machine having, in combination, a driver, an awl arranged to form fastening receiving holes in the work and to feed the work to bring the fastening receiving hole formed therein into alignment with the driver, a throat member movable transversely of the line of feed of the work to present fastenings to the operation of the driver for insertion into the work, and means for pressing the throat member against the surface of the work to support the fastenings at the point of fastening insertion. 100
25. 6. A fastening inserting machine having, in combination, a driver, an awl for forming fastening receiving holes in a work piece presented thereto and for feeding the work to bring the fastening receiving hole into position to receive a fastening, a throat member movable in one direction transverse to the path of feed of the work to present fastenings to the operation of the driver and movable in a different direction to provide a continuous support for the fastenings terminating at the surface of the work, and means for operating the driver to insert a fastening into the work. 105
30. 7. A fastening inserting machine having, in combination, means for forming fastening-receiving holes in the work, means for inserting fastenings in the holes formed in the work, and means movable relatively to said hole forming means for presenting fastenings to the operation of the inserting means, said means being movable also in the same direction as the inserting means into engagement with the work prior to the fastening-inserting operation. 110
35. 8. A fastening inserting machine having, in combination, means for forming fastening-receiving holes in the work, means for inserting fastenings in the holes formed in the work, and means constructed and arranged yieldingly 115
- means for severing fastenings from a strip of fastening material and presenting them to the operation of the inserting means, and means for yieldingly pressing the last named means into engagement with the work prior to the inserting operation. 120
9. A fastening-inserting machine having a driver, an awl arranged to pierce the bottom of a shoe mounted on a last and having a rubber sole, and means arranged to sever fibre fastenings from a strip of fibre fastening material and to move them into line with the driver, said means being movable also into forceful engagement with the work to prevent deflection of the fastenings as they are inserted into the work. 125
10. A fastening-inserting machine having, in combination, a driver, an awl arranged to pierce the bottom of a shoe mounted on a last and having a rubber sole, means for severing a fastening from a strip of fastening material and presenting the fastening to the operation of the driver, and means for causing the last named means to engage the sole to compress that portion of the sole into which the fastening is to be inserted in the direction of the length of the fastening-receiving hole formed therein prior to and during the fastening-inserting operation and then to release the compressed portion of the sole to permit the rubber of the sole to close about the inserted fastening. 130
11. A fastening-inserting machine for attaching rubber soles to shoes having, in combination, a fastening inserting driver, an awl arranged to form fastening receiving holes in the work and to feed the work to bring the fastening receiving hole into position to receive a fastening, and a member movable transversely to the line of feed of the work for feeding a fastening into alignment with the driver, said member being arranged to apply a substantial compressing force to the material of the sole in the immediate vicinity of the fastening receiving hole prior to and during insertion thereof of the fastening. 135
12. A fastening-inserting machine for attaching rubber soles to shoes having, in combination, a fastening inserting driver, means for forming fastening receiving holes in the work and for feeding the work to bring the fastening receiving hole formed therein into line with the driver, and means movable in a direction transverse to the line of drive to move a fastening into the line of drive and movable in the line of drive to compress the material of the sole surrounding a fastening receiving hole prior to the insertion therein of a fastening and then releasing the pressure to permit the rubber of the sole to close about the inserted fastening. 140
13. A fastening inserting machine having a driver, an awl arranged to pierce the bottom of a shoe to form a fastening receiving hole therein, a throat member arranged to sever fastenings from a strip of fastening material and to present the fastenings to the operation of the driver, and means for forcibly thrusting the throat member against the sole at the point of fastening insertion to support the fastening during the inserting operation. 145
14. A fastening inserting machine having a driver, an awl arranged to form fastening receiving holes in the work piece, a throat member arranged to sever fastenings from a strip of fastening material and to present the fastenings to the operation of the drive for insertion into the holes formed in the work by the awl, and means constructed and arranged yieldingly 150

- to thrust the throat member against the sole at the place where the fastening is to be inserted to support the fastening during the inserting operation and to return the throat member positively to its inoperative position after a fastening has been inserted into the work. 80
15. A fastening inserting machine having, in combination, a driver, an awl arranged to pierce the bottom of a shoe having a rubber sole to form a fastening receiving hole therein, a throat member arranged to sever a fastening from the strip of fastening material and to present the fastening to the operation of the driver, means for moving the throat member bodily toward the work until the rubber of the sole in the immediate vicinity of the fastening receiving hole is under compression, and means for operating the driver to insert a fastening into the hole. 85
16. A fastening-inserting machine having, in combination, an awl arranged to form fastening receiving holes in the work, a driver arranged to insert fastenings in the holes formed in the work by the awl, a throat member for presenting fastenings to the driver, means for moving the throat member into engagement with the work including a spring connection arranged to yield when the throat member contacts with the surface of the work, and means for operating the driver to insert the fastenings. 90
30. 17. A fastening inserting machine for attaching rubber soles to shoes having, in combination, a driver, an awl, means for causing the awl to penetrate the work to a depth determined by the thickness of the work and to feed the work to bring the hole formed therein into the path of the driver, and a throat member arranged to present for insertion by the driver, fibre fastenings of a length determined by the depth to which the awl has penetrated the work in forming holes for the fastenings, said throat member being arranged also to apply a compressing force to the sole to reduce the thickness of the measured portion of the sole to prevent spreading of the upper end of the fibre fastenings during the inserting operation. 100
40. 18. A fastening-inserting machine having a driver, an awl, means for operating the awl constructed and arranged to cause the awl to pierce the bottom of a shoe mounted on a last and having a rubber sole to a depth determined by the thickness of the work, means for severing from a strip of fibre fastening material fastenings of a length determined by the thickness of the work and presenting them to the operation of the driver for insertion into the holes formed by the awl, said means acting also to apply a compressing force to the sole thereby reducing the thickness of that portion of the sole into which the fastening is to be inserted and preventing crippling of the fastenings, and means for operating the driver to insert a fastening into the compressed portion of the sole. 110
50. 19. A fastening-inserting machine having, in combination, a driver, an awl arranged to pierce the bottom of a shoe having a rubber sole, a work support, a throat member arranged to sever a fastening from a strip of fastening material and to move the fastening into line with the driver, means for causing relative movement of approach between the throat member and the work support until the rubber of the sole is under compression, and means for operating the driver to insert a fastening carried by the throat member into the hole. 115
60. 20. A fastening-inserting machine for attaching rubber soles to shoes having, in combination, a driver, an awl arranged to form fastening receiving holes in the work and to feed the work to bring the fastening receiving holes formed therein into line with the driver, a work support, a throat member arranged to sever fibre fastenings from a strip of fibre fastening material and to move the fastening into alignment with the driver, and means for causing relative movement of the throat member and the work support to compress the rubber of the sole in the direction of the length of a fastening receiving hole formed therein by the awl, and means for operating the driver to insert a fastening into the compressed portion of the sole. 120
70. 21. A fastening inserting machine for attaching rubber soles to shoes having, in combination, a driver, an awl arranged to pierce the bottom of a shoe mounted on a last and having a rubber sole, means for moving the awl transversely of the machine to bring the hole formed in the work into line with the driver, a fastening receiving throat movable from fastening receiving position into position to align the fastening with the driver, means for forcibly thrusting the throat member into engagement with the sole at the place where the fastening is to be inserted to prevent crippling of the fastening during the inserting operation, and means for operating the driver to insert the fastening into the hole. 125
80. 22. A fastening-inserting machine having, in combination, a driver, an awl arranged to form fastening-receiving holes in a work piece presented thereto and to feed the work to bring the fastening-receiving hole formed therein into fastening-inserting position, a throat member, means for feeding fastening material into said throat member the length of feeding movement of which is controlled by the depth to which the awl penetrates the work, means for moving said throat member toward the driver to sever a fastening and to bring the fastening into alignment with the driver, cam operated means for thereafter moving the throat member and the fastening toward the work, and means for operating the driver to insert the fastening carried by the throat member into the hole formed in the work by the awl. 130
90. 23. A fastening-inserting machine for attaching rubber soles to shoes having, in combination, a driver, an awl, means for causing the awl to penetrate the work to a depth determined by the thickness of the work and to feed the work to bring the hole formed therein into the path of the driver, a throat member arranged to present for insertion by the driver fastenings of a length determined by the depth to which the awl has penetrated the work in forming holes for the fastenings, and means for thrusting the throat member against the sole to compress the rubber of the sole in the direction of the length of the fastening-receiving hole formed therein by the awl comprising a lever, means for rocking the lever, and a spring connection between the lever and the throat arranged to permit the lever to continue its rocking movement when the throat member has come to rest by reason of the resistance presented by the material of the sole. 135
100. 24. A fastening-inserting machine for attaching rubber soles to shoes having, in combination, a driver, an awl arranged to form fastening-receiving holes in the work and to feed the work to bring the fastening-receiving hole formed therein into fastening-inserting position, a throat 140
110. 25. 150

member, means for feeding fastening material into said throat member the length of feeding movement of which is controlled by the depth to which the awl penetrates the work, means for moving said throat member toward the driver to sever a fastening and to bring the fastening into the path of the driver, and means for moving the throat member toward the work to compress the rubber of the sole in the immediate

vicinity of the fastening-receiving hole formed therein by the awl comprising a lever, a cam for rocking said lever, and connections between the lever and the throat member including a compression spring arranged to yield to permit the throat member to come to rest by reason of the resistance offered by the material of the sole. 80
